CLAIM

The ornamental design for the stacked animal feeding bowls, as shown and described.

DESCRIPTION

A portion of the disclosure of this patent document contains material to which a claim for copyright is made. The copyright owner has no objection to the facsimile reproduction by anyone of the patent document or the patent disclosure as it appears in the Patent and Trademark Office patent file or records, but reserves all other copyright rights whatsoever.

FIG. 1 is a perspective view of the stacked animal feeding bowls;

FIG. 2 is a front elevational view thereof;

FIG. 3 is a right side elevational view thereof;

FIG. 4 is a rear side elevational view and mirror image of FIG. 2;

FIG. 5 is a left side elevational view and mirror image of FIG. 3;

FIG. 6 is a top plan view thereof; and,

FIG. 7 is a bottom plan view thereof.
